Primary Examiner — Caron D Veynar*Assistant Examiner* — Abraham Bahta(74) *Attorney, Agent, or Firm* — Pillsbury Winthrop Shaw Pittman LLP**CLAIM**

The ornamental design for a display assembly, as shown and described.

DESCRIPTION

FIG. 1 is a front perspective view according to a first embodiment of the display assembly;

FIG. 2 is a top view thereof;

FIG. 3 is a front view thereof;

FIG. 4 is a left side view thereof, the right side view thereof being a mirror image thereof;

FIG. 5 is a rear view thereof;

FIG. 6 is a rear perspective view thereof;

FIG. 7 is a front perspective view according to a second embodiment of the display assembly;

FIG. 8 is a top view thereof;

FIG. 9 is a front view thereof;

FIG. 10 is a left side view thereof, the right side view thereof being a mirror image thereof;

FIG. 11 is a rear view thereof; and,

FIG. 12 is a rear perspective view thereof.

Where included, three adjacent parallel, oblique lines on a surface are used to show transparency. One feature of the ornamental design in FIGS. 1-12 resides in the article being open-ended.
